UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

LIGHTING MEANS.

1,352,252.

Specification of Letters Patent. Patented Sept. 7, 1920.

Application filed May 10, 1917. Serial No. 167,725.

To all whom it may concern:

Be it known that I, ETHAN I. DODDS, a citizen of the United States, and a resident of Pittsburgh, in the county of Allegheny and State of Pennsylvania, have invented 5 certain new and useful Improvements in Lighting Means; and I do hereby declare the following to be a full, clear, and exact description of the invention, such as will enable others skilled in the art to which it 10 pertains to make and use the same.

This invention relates to lighting means,—the object of the invention being to provide a lamp globe with a coating which, upon 15 being excited by a momentary flash or ray of light, will become luminous and remain so for an appreciable period of time, and radiate the light so produced and stored.

With this object in view, the invention 20 consists in certain novel features as herein-after set forth and pointed out in the claim.

The accompanying drawing is a view in section showing an embodiment of my invention.

25 1 represents a transparent globe having on its interior surface a thin coating 2 of phosphorescent material which will absorb light rays and emit the same for a period of time. The material which I propose to use

30 consists of a suitable oxid or zinc or calcium sulfid having mixed therewith an infinitesimal quantity of radium, which may be in the form of a salt of radium. The amount of radium used may be so small that the globe

35 will not be luminous in the dark, but when a light is placed in the globe, for a brief period, the rays will be absorbed by the coating, the scintillations darting back and forth, and the coating and therefore the globe will be rendered luminous and will remain so for an appreciable period after the 40 artificial light shall have been extinguished or removed.

A flash of light within the globe will suffice to excite the illuminating coating and 45 such flashes may be repeated as occasion may require, or the coating might be energized with the use of sunlight.

The coated globe 1 may be sealed by a cup 3 which carries an incandescent electric 50 lamp 4,—said cup containing an electromagnet 5, the coil of which may be included in series with the lamp filament in an electric circuit containing a switch 6, or if desired, a permanent magnet may be employed. The 55 switch may be held normally open by a spring 7. The light-absorbing coating in the globe is thus brought within the zone of magnetic lines of force and I have found that the brilliancy of the glow of the coating 60 will thereby be enhanced.

My improvements provide a cold light; one which can be handled without bad effects, either to the eyes or to the body; one which will glow under water; which will 65 glow brilliantly when in the zone of a magnet; and which can be energized by sunlight and still increase in intensity when in a magnetic zone.

Having fully described my invention what 70 I claim as new and desire to secure by Letters-Patent, is:—

Illuminating means comprising a globe containing a coating of phosphorescent material, a source of light within the globe, and 75 means for providing a magnetic field in the zone of said coating.

In testimony whereof, I have signed this specification in the presence of a subscribing witness.

ETHAN I. DODDS.

Witness:

F. H. ALLISON.
